KNITTING MACHINE ATTACHMENT

Robert H. Sperzel, New Haven, Conn., assignor to
The Whitney Blake Company, Hamden, Conn.,
a corporation of Connecticut

Application July 15, 1943, Serial No. 494,780

18 Claims.

(Cl. 66—166)

This invention relates to machines for knitting covers on electric wires and cables, and more particularly to means for preventing the making of a faultily covered product.

In the covering of electric wires by knitting, it sometimes occurs that although the threads do not break, the knitting operation becomes faulty so that the covering, instead of being neat and tight, is loose and has loops of thread extending from the covering.

Heretofore, attempts have been made to detect when the knitting machine was not properly functioning to provide the desired covering, but these for one reason or another have not been satisfactory in operation and use.

The problem has been solved, however, by the present invention, by the provision of a detector mechanism in which a switch lever connected to the usual machine stopping mechanism (now used to detect the breaking of threads) is operated by a feeler which is held in the path of the advancing covered wire and which has a barb or fang positioned to catch any looped threads which project from the knitted cover as a result of a stitch being lost or the covering otherwise being loosely knitted.

According to the present invention, the feeler is yieldingly urged toward the advancing covered wire, and its barb or fang is positioned slightly back of its outer or guiding edge so that the detector will operate on wires of different diameters and regardless of changes in the diameter of the wire, and will not shut off the machine unless loops from a loose part of the covering catch onto the barb.

Further, according to the present invention, the feeler is so mounted and controlled that when a loop is caught on the barb, the feeler is carried upwardly in the direction of travel of the wire and then suddenly moves upwardly and away from the wire and at the same time causes the circuit to the machine stopping mechanism to be closed. The provision of the feeler so that it will move in the direction of the wire and then in advance of the wire and away from it avoids the danger of the covering being ripped and the threads broken by reason of the barbs engaging the loops of the threads.

In the form of the invention herein illustrated as exemplary thereof, the feeler and switch lever are made in one piece and the snap action movements of the feeler and switch are controlled by a spring which is placed under tension during the first part of the movement of the feeler and which, upon moving across the center of oscil-

lation of the feeler, completes the upward and receding movement of the feeler, and at the same time causes the circuit to be closed.

The device of the present invention may be made as an attachment to existing machines in which case, as shown, the feeler and switch are mounted on a block suitably supported on a fixed part of the machine so that the end of the feeler is in position to engage the advancing wire end closed by a covering of knitted fabric.

Other features and advantages will herein-after appear.

In the accompanying drawing which illustrates one form of this invention—

15 Fig. 1 is an elevation, partly in section, of a knitting machine showing the present invention attached thereto.

Fig. 2 is a plan view of the attachment of the present invention.

20 Fig. 3 is a side view, partly in section, of the attachment of the present invention showing the feeler lever in operated position and showing its relation to the guide tube of the knitting machine.

25 Fig. 4 is a vertical section taken on the line 4—4 of Fig. 3.

As shown in the accompanying drawing, the knitting machine comprises a main frame member 10 having a suitable bracket 11 and a member 12 which carries the yarn guides 13. The electric wire or cable onto which a cover is to be knitted is guided upwardly through a guide tube 14, another guide 15 spaced from the guide tube 14, and finally passes upwardly and out of the machine through a guide tube 16 and over a guide 17 to a reel (not shown) upon which it is wound. The knitted covering which is made by the operations of the needles 13a in the usual manner passes thru the space 18 between the guide tube 14 and the guide 15 around the wire and then upwardly through the guide 15 and the guide tube 16.

Suitable detectors 19 are provided with means over which the threads to be knitted pass so that in case a thread should break a switch is operated to close a circuit including the wire 20 which is connected to stop mechanism for the machine in the well known manner so that the knitting mechanism will automatically stop and thereby 50 signal the attendant who can repair the break and start the machine operating again.

In the operation of these knitting machines, one attendant or operator usually takes care of a fairly large number of machines, and it has happened that due to some trouble other than the

breaking of a thread the knitting operation becomes faulty. For instance, in the knitting operation, a stitch might be dropped by a needle, causing the covering to be so poorly knitted as to be unsuitable for its intended purpose.

Heretofore, the detecting device provided on the machines would not indicate that the covering was not being knitted properly, and before the operator again reached a particular machine to check the work, many feet of faultily covered cable had been made.

The present invention obviates this difficulty by immediately detecting and indicating to the operator when the cover is improperly knitted. Normally, when the cover is being knitted properly, the threads of the covering lie tightly against the external surface of the wire or cable. However, when the knitting becomes loose and hence faulty, loops of thread project beyond the cable. The present invention provides a feeler device which detects the presence of such loops and gives an alarm, as, for instance, by the stopping of the machine so that the operator may correct the fault before too great an amount of faulty covering has been made.

In the embodiment of this invention, herein illustrated, as exemplary thereof, this is accomplished by providing a feeler device in the form of a lever 21 which is mounted on a suitable block 22 attached by any suitable means, as by a collar 23 to a vertical post 24 forming part of the machine. The post 24 constitutes the support for the guide 17. As thus made, the device of the present invention can be furnished as an attachment to existing machines, but it should be understood that the present invention may be applied in many different ways to the machines.

The block 22 which carries the feeler lever 21 is provided with a V-shaped guide slot 25 and is mounted in the path of the ascending cable.

The feeler lever 21 is mounted on the block 22 by a screw 26 so as to extend into the V-shaped slot 25, and has a V-shaped notch 27 at its outer end engaged by a spring 28 anchored at 29 on the block. In its normal operating position, which is its horizontal position shown in Fig. 1, the feeler lever 21 is urged inwardly, i. e., to the left as shown, so that a smooth or rounded nose portion 30 of the lever is in position to engage the cable C indicated in dotted lines in Fig. 1. The nose 30 is yieldingly urged against the cable by the spring 28, the slot 31 in the lever permitting the necessary longitudinal movement of the feeler for this purpose. So long as the covering on the cable is properly formed and tight, the feeler lever 21 will remain in the position shown in Fig. 1. If, however, the knitted covering on the wire is loose so as to throw up loops, such loops will catch onto a barb or beak portion 32 on the feeler and the advancing wire will cause the feeler to travel upwardly with it. During this upward movement of the feeler, the rear end of the lever is rocked downwardly, deflecting and placing the spring 28 under tension and ultimately carrying the end of the spring engaging the V-shaped notch 27 across the axis of oscillation of the lever 21, at which time the spring will expand or straighten out and cause the feeler 21 to be rapidly moved upwardly and away from the advancing wire so as to disengage the loop and prevent the covering from being ripped thereby.

When the feeler 21 reaches its uppermost position under the influence of the spring 28 (see Fig. 3), a switch portion 33 on the lever engages

a contact 34 which is connected by a wire 35 to the wire 20 through one of the posts of a detector device 19, thus closing the circuit to the stop mechanism for the machine and causing the machine to be stopped. The stopping of the machine will indicate to the operator that something is wrong, and when the operator inspects the machine and observes that the feeler 21 has been raised, he will be advised that the machine stopped because of a fault in the knitted covering.

By providing the snap spring 28, the switch portion 33 of the feeler is kept in engagement with the contact 34 even though the loop in the thread which caused the feeler to be operated should be released from the barb 32 or should be broken. When the operator has corrected the faulty operation which resulted in the tripping of the feeler 21, the feeler is returned by manual operation to the position shown in Fig. 1 in which it remains so long as the covering on the wire is sufficiently tight and close to prevent the formation of loops.

It should be noted that the normal contact between the wire covering and the feeler is at the rounded nose 30, and that the bar 32 is set slightly behind its rounded nose. Hence, there is no danger of the barb 32 getting into the loops of threads of a properly knitted covering, and it is only when projecting loops or faults are formed that the barb can be engaged and caught onto.

With the use of the present invention, in the event of an improper operation of the machine resulting in an imperfectly knitted covering, only that portion of the wire between the feeler 21 and the knitting needles need be removed or discarded, for the feeler will detect the improper covering before the wire actually leaves the machine.

Thus, a substantial saving in material is effected by the present invention in addition to a saving of the production time of the machine which would otherwise be lost by the making of much faulty covering unobserved by the operator, and time saved in making repair to the covering.

Variations and modifications may be made within the scope of this invention and portions of the improvements may be used without others.

I claim:

1. In a machine for knitting a fabric covering on electric wires and cables, mechanism for knitting a covering about the wire; means for guiding and advancing the covered wire axially and away from the knitting mechanism; a circuit connected with means for stopping the machine; and means including a slidable and pivotally mounted feeler in the path of the covered wire and actuated by being encountered by a fault in the covering of the advancing wire to move longitudinally with the wire, and a switch connected in said circuit and operated by the movement of said feeler about the pivot thereof to control the circuit and cause the mechanism to stop when the feeler is actuated.

2. In a machine for knitting a fabric covering on electric wires and cables, mechanism for knitting a covering about the wire; means for guiding and advancing the covered wire axially and away from the knitting mechanism; a circuit connected with means for stopping the machine; and means including a slidable and pivotally mounted feeler in the path of the covered wire and actuated by being encountered by a

fault in the covering of the advancing wire to move longitudinally with the wire, and a switch connected in said circuit and operated by said feeler to control the circuit and cause the mechanism to stop when the feeler is actuated, said feeler being yieldingly urged to slide toward the wire and having its normal position controlled thereby.

3. In a machine for applying a fabric covering to electric wires and cables, mechanism for forming a covering about the wire; means for guiding and advancing the covered wire axially and away from the cover-forming mechanism; a circuit connected with means for stopping the machine; and means including a feeler in the path of the covered wire and actuated by and traveling longitudinally with the wire upon being encountered by a fault in the covering of the advancing wire and moving away from the wire incident to such travel, and a switch connected in said circuit and operated in response to the movement of said feeler to control the circuit and cause the mechanism to stop when the feeler is actuated.

4. In a machine for applying a fabric covering on electric wires and cables, mechanism for forming a fabric covering about the wire; means for guiding and advancing the covered wire away from the cover-forming mechanism; a circuit connected with means for stopping the machine; means including a feeler in the path of the covered wire and actuated by and traveling with the wire upon being encountered by a fault in the covering of the advancing wire, and a switch connected in said circuit and operated by said feeler to control the circuit and cause the mechanism to stop when the feeler is actuated; and a spring energized by the movement of the feeler as it travels with the wire and adapted to automatically move the feeler upwardly and away from the cable when the feeler has traveled a predetermined amount.

5. In a machine for applying a fabric covering on electric wires and cables, mechanism for forming a covering about the wire; means for guiding and advancing the covered wire away from the cover-forming mechanism; a circuit connected with means for stopping the machine; means including a feeler in the path of the covered wire and actuated by and traveling with the wire upon being encountered by a fault in the covering of the advancing wire, and a switch connected in said circuit and operated by said feeler to control the circuit and cause the mechanism to stop when the feeler is actuated; and a spring yieldingly urging the feeler toward the wire and energized by the movement of the feeler as it travels with the wire so as to automatically move the feeler upwardly and away from the wire when the feeler has traveled a predetermined amount.

6. In a machine for applying a fabric covering on electric wires and cables, mechanism for forming a fabric covering about the wire; means for guiding and advancing the covered wire away from the cover-forming mechanism; a circuit connected with means for stopping the machine; means including a feeler in the path of the covered wire and actuated by and traveling with the wire upon being encountered by a fault in the covering of the advancing wire, and a switch connected in said circuit and operated by said feeler to control the circuit and cause the mechanism to stop when the feeler is actuated; and a snap action spring adapted to rapidly move

the feeler upwardly and away from the wire when the feeler has traveled a predetermined amount.

7. In a machine for applying a covering to an electric wire or cable, mechanism for forming a covering about the wire; means for guiding and advancing the covered wire axially and away from the cover-forming mechanism; a movable feeler in the path of the covered wire and actuated by being encountered by a fault in the covering of the advancing wire to move longitudinally with the wire; and a switch operated by said feeler to control a circuit and cause an alarm to be given when the feeler is actuated, said feeler moving with the fault as the wire advances and releasing the fault incident to operating the switch.

8. For machines adapted to form a covering about electric wires and cables and having means for guiding and advancing the covered wire away from the cover-forming mechanism and a circuit connected with means for stopping the machine, an attachment comprising a pivoted feeler yieldingly mounted to project into the path of the covered wire and movable by the covered wire upon encountering a fault in the covering of the advancing wire; and a switch connected in said circuit and operated by the movement of said feeler to control the circuit and cause the mechanism to stop when the feeler is actuated.

9. In a machine for applying a covering on an electric wire and cable, mechanism for forming a covering about the wire; means for guiding and advancing the covered wire away from the cover-forming mechanism; and means including a feeler in the path of the covered wire and actuated by being engaged by a fault in the covering of the advancing wire, and a snap switch operated by said feeler to control an electric circuit and when the feeler is actuated, said snap switch remaining in operated position even though the fault becomes disengaged from the feeler.

10. For machines adapted to apply a covering about electric wires and cables and having means for guiding and advancing the covered wire away from the covering-applying mechanism, an attachment comprising a pivotally mounted feeler in the path of the covered wire and actuated by being encountered by a fault in the covering of the advancing wire, said feeler moving in the direction of the advancing wire and away from the wire to release the fault to prevent damage to the cover; and means operated incident to the movement of said feeler to indicate when the feeler is actuated.

11. In a machine for applying a fibrous covering on electric wires and cables, mechanism for forming a fibrous covering about the wire; means for guiding and advancing the covered wire away from the cover-forming mechanism; a circuit connected with means for stopping the machine; and means including a feeler urged into engagement with the covered wire and having a barb spaced from the wire adapted to catch onto faults in the covering of the advancing wire and be actuated thereby, and a switch connected in said circuit and operated by said feeler to control the circuit and cause the mechanism to stop when the feeler is actuated.

12. In a machine for applying a fabric covering on electric wires and cables, mechanism for forming a covering about the wire; means for guiding and advancing the covered wire away from the cover-forming mechanism; a circuit connected with means for stopping the machine;

and means including a feeler having a smooth surface yieldingly urged against the advancing wire and a barb spaced from said smooth surface and adapted to catch onto projecting loops of thread caused by a fault in the covering of the wire to be actuated thereby, and a switch connected in said circuit and operated by said feeler to control the circuit and cause the mechanism to stop when the feeler is actuated.

13. For machines adapted to form a fabric covering about electric wires and cables and having means for guiding and advancing the covered wire away from the cover-forming mechanism, an attachment comprising a feeler having a smooth edge surface yieldingly urged against the advancing wire, and a barb spaced from the smooth edge surface and adapted to catch onto projecting loops of thread caused by a fault in the covering of the wire to be actuated thereby; and a switch operated by said feeler to control a circuit and cause an alarm to be given when the feeler is actuated.

14. A detector for a wire or cable covering machine comprising a base adapted to be mounted on the machine adjacent the covered wire; cover-fault detecting means including a feeler having a longitudinally extending elongate aperture therein; pivot means mounted on the base and extending through the aperture to slidably and pivotally mount the feeler thereon; and resilient means engaging the back of the feeler to yieldingly slide the feeler toward and into the path of the advancing covered wire to be engaged by faults in the cover thereon, the engagement of the faults moving the feeler in the direction of the advancing wire and about the pivot, said movement of the feeler energizing the resilient means to cause the feeler to snap away from the wire after a predetermined movement of the feeler to release the same from the fault and prevent damage to the wire.

15. A detector for a wire or cable covering machine comprising a base adapted to be mounted on the machine adjacent the cable-covering means; cover-fault detecting means including a feeler having a longitudinally extending elongate aperture therein; pivot means mounted on the base and extending through the aperture to slidably and pivotally mount the feeler thereon; resilient means engaging the back of the feeler to yieldingly slide the feeler toward and into the path of the advancing covered wire to be engaged by faults in the cover thereon, the engagement of the faults moving the feeler in the direction of the advancing wire and about the pivot, said movement of the feeler energizing the resilient means to cause the feeler to snap away from the wire after a predetermined movement of the feeler to release the same from the fault and prevent damage to the wire; and means operated in response to the movement of the feeler for indicating the detection of a fault in the cover.

16. A detector for a wire or cable covering machine comprising a base adapted to be mounted on the machine adjacent the cable-covering means; cover-fault detecting means including a

feeler having a longitudinally extending elongate aperture therein; pivot means mounted on the base and extending through the aperture to slidably and pivotally mount the feeler thereon; resilient means engaging the back of the feeler to yieldingly slide the feeler toward and into the path of the advancing covered wire to be engaged by faults in the cover thereon, the engagement of the faults moving the feeler in the direction of the advancing wire and about the pivot, said movement of the feeler energizing the resilient means to cause the feeler to snap away from the wire after a predetermined movement of the feeler to release the same from the fault and prevent damage to the wire; and switch means operated in response to the movement of the feeler for controlling a circuit to stop the machine.

17. A detector for a wire or cable covering machine comprising a base adapted to be mounted on the machine adjacent the cable-covering means; cover-fault detecting means including a feeler having a longitudinally extending elongate aperture therein; pivot means mounted on the base and extending through the aperture to slidably and pivotally mount the feeler thereon; resilient means engaging the back of the feeler to yieldingly slide the feeler toward and into the path of the advancing covered wire to be engaged by faults in the cover thereon, the engagement of the faults moving the feeler in the direction of the advancing wire and about the pivot, said movement of the feeler energizing the resilient means to cause the feeler to snap away from the wire after a predetermined movement of the feeler to release the same from the fault and prevent damage to the wire; and switch means operated in response to the movement of the feeler for controlling a circuit to stop the machine.

18. A detector for a wire or cable covering machine comprising a base adapted to be mounted on the machine adjacent the covered wire; cover-fault detecting means including a feeler having a longitudinally extending elongate aperture therein; pivot means mounted on the base and extending through the aperture to slidably and pivotally mount the feeler thereon; and resilient means engaging the back of the feeler to yieldingly slide the feeler toward and into engagement with the wire, means on the feeler spaced from the wire-engaging part thereof and projecting into the path of the advancing covered wire to be engaged by faults in the cover thereon, the sliding movement of the feeler enabling the detector to operate on wires of different diameters, the engagement of the faults moving the feeler in the direction of the advancing wire and about the pivot, said movement of the feeler energizing the resilient means to cause the feeler to snap away from the wire after a predetermined movement of the feeler to release the same from the fault and prevent damage to the wire.
